OR D 4,219

John Hegarty. Design Fountain.

4219

PATENTED JUL 12 1870

United States Patent Office.

JOHN HEGARTY, OF JERSEY CITY, NEW JERSEY.

Design No. 4,219, dated July 12, 1870.

DESIGN FOR A FOUNTAIN.

The Schedule referred to in these Letters Patent and making part of the same.

To all whom it may concern:

Be it known that I, JOHN HEGARTY, of Jersey City, in the county of Hudson and State of New Jersey, have invented a new and original Design for Fountain; and I do hereby declare that the following is a full, clear, and exact description thereof, which will enable others skilled in the art to make and use the same, reference being had to the accompanying photograph forming part of this specification.

The photograph represents a perspective view of my new design for fountain.

This invention relates to a new design for the pedestal, base, body, top, handle, and crown of an ornamental fountain.

The pedestal or foot A, by which the fountain B is supported, is made in form of a column, with an enlarged capital, a, which constitutes the table for the fountain to stand upon, and with an enlarged base, b, as shown.

The shaft proper of the column is ornamented by a representation, c, of the sun, in relief.

The base C of the fountain is made in form of a shell, resting upon four feet, d, and large enough to serve as flower-pot under the fountain.

The body B of the fountain is ornamented by relief representations of tulips e and other flowers, herbs, &c., and of bee-hives f, as shown.

The upper edge g of the fountain is folded outward and scalloped, as shown.

The handles D are secured to the ends of the foun-

tain, within niches provided therein, and are made in form of hands of figures, set up within said niches, as shown.

The top E of the fountain is made in form of a shell, with an upward-projecting central flower, F, as shown.

The crown of the fountain is formed by a light frame, G, fastened to the ends of the fountain, and composed of two tiers, of gothic form, as is clearly shown in the photograph.

Having thus described my invention,

What I claim as new, and desire to secure by Letters Patent, is—

1. The design for the pedestal A of the fountain, as set forth.
2. The design for the top E, provided with the central flower F, as shown and described.
3. The design for the fountain-body, which is provided with the flowers and other ornaments in relief, as set forth.
4. The design for the hand-shaped handles D, formed on the figures that are put into the niche in the fountain, as set forth.
5. The design for the ornamental head or crown G of the fountain, as set forth.

JOHN HEGARTY.
